CLAIM

The ornamental design for a male connector, as shown and described.

DESCRIPTION

FIG. 1 is a front and right perspective view of a male connector showing the new design; FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a rear and top perspective view thereof;

FIG. 9 is a rear and bottom perspective view thereof; and,

FIG. 10 is an enlarged view of portion 37 in FIG. 1.

The dot dash broken lines shown define the bounds of the claimed design and form no part thereof.

1 Claim, 8 Drawing Sheets(56)
